United States Patent Office

Des. 214,028
Patented May 6, 1969

214,028

DOOR CLOSER

Michael M. Weiner, Los Angeles, Calif.
(P.O. Box 36, Woodland Hills, Calif. 91365)

Filed May 16, 1968, Ser. No. 11,961

Term of patent 14 years

Int. Cl. D8—03

U.S. Cl. D8—203

FIGURE 1 is a perspective view of a door closer, showing my new design;

FIGURE 2 is a top plan view thereof;

FIGURE 3 is a front elevation view thereof, the spring being broken away for clarity of illustration;

FIGURE 4 is a rear elevation view thereof;

FIGURE 5 is a side elevation view thereof, as taken along line 5-5 in FIGURE 2 and partly sectional;

FIGURE 6 is a side elevation view thereof, as taken along line 6-6 in FIGURE 2 and partly sectional; and

FIGURE 7 is a top plan view thereof in another position.

I claim:

The ornamental design for a door closer, substantially as shown.
